UNITED STATES PATENT OFFICE

FREDERICK J. THELER, OF CINCINNATI, OHIO, ASSIGNOR TO CINCINNATI GRINDERS INCORPORATED, OF CINCINNATI, OHIO, A CORPORATION OF OHIO

GRINDING MACHINERY

Application filed May 20, 1929. Serial No. 364,377.

This invention relates to improvements in grinding machinery and more especially to that type of machine commercially known as a centerless grinder.

- 5 One of the principal objects of the present invention is the provision of a novel and improved structure of feed mechanism for supplying work in operative position to the machine for grinding action thereon.
- 10 A further object of the invention is the provision of means for satisfactorily retaining out of balance work pieces in proper operative position during the grinding operation.
- 15 An additional object of the invention is the provision of a combined work feeding support and an ejecting mechanism particularly adapted for use in conjunction with a machine, as aforesaid, which will satisfactorily present the work to the grinding throat, maintain same in a self determined position within the throat during grinding, independent of the movable or normally work engaging portion of the fixture, and will subsequently properly withdraw and discharge the completed work piece.

A further object of the invention is the provision of an automatic control for the mechanism aforesaid whereby the cyclic shifting thereof will be effected in proper timed relation to the other automatic movements of the machine whereby the rate of production of the machine may be automatically determined and the operator relieved of all labor except suitable intermittent supplying of work pieces to the feeding mechanism.

Other objects and advantages of the present invention should be readily apparent by reference to the following specification, considered in conjunction with the appended drawings illustrative of certain embodiments thereof, and it will be understood that I may make any modifications in the specific structural details hereinafter disclosed, within the scope 40 of the appended claims, without departing from or exceeding the spirit of the invention.

Figure 1 is a front elevation of a manually controlled embodiment of the invention.

Figure 2 is an enlarged view of the parts at 45 the grinding throat.

Figure 3 is a transverse section as on line 3-3 of Figure 2.

Figure 4 is a plan view of the parts at the grinding throat.

Figure 5 is a section through a portion of 55 the work and outer supports therefor on the line 5-5 of Figure 3.

Figure 6 is a fragmentary transverse section on line 6-6 of Figure 3.

Figure 7 is an end view, partially in section and partially in elevation, of a completely 60 automatic machine.

Figure 8 is a front view, partially in elevation and partially in section, illustrating the automatic control mechanism, and 65

Figure 9 is an elevational view of the throat of a completely automatic machine.

In the drawings the numeral 10 designates the bed of a centerless grinder having the head 11 rotatably supporting the grinding wheel 12 operable in a clockwise direction at a high grinding rate of speed. The bed is further provided with ways 11' for slide unit 13 having the fixture supporting bracket member 14 suitably secured thereon. In addition, slide 13 is provided with ways 15, for the regulating wheel unit 16, securable in adjusted position thereon as by clamp 17 and bearing the suitably driven control or regulating wheel 18. This latter is also actuated in a clockwise direction but at a slow work controlling rate of speed, whereby its inner operative surface will move slowly upward, presenting a constant and uniform moving friction surface to the work piece, insuring its 85 rotation at a constant and uniform rate.

The bracket 14 has a projection 19 slotted as at 20 to receive the angle top work rest blade 21 retained in adjusted position by clamp screws 22.

The grinding and regulating wheels and work rest, together, form a three point contact, respectively supporting, controlling and grinding predetermined portions such as the rib 23 of work piece 24.

The particular mechanism here illustrated is designed to generate a true cylindrical surface on the portion 23 normal to the terminal face 25 of the work piece. It will be noted the major mass of the work piece is laterally 100

disposed as respects the grinding throat, presenting an unbalanced condition which would normally cause the work piece, if unsupported, to topple over or fall out of the grinding throat. To prevent occurrence of this action during grinding and maintain the work piece with its axis in proper relation to the operative faces of the wheels, use is made of certain terminal steadyng members.

10 Extending upward from bracket 14, at the rear of the machine, is a plate or support 26 slotted, as at 27, to permit of vertical adjustment thereon of bearing block 28, which rotatably supports, through the medium of the 15 anti-friction thrust bearings 29, the spindle 30 having a suitable head 31. The spindle is preferably mounted with extreme accuracy and is designed to be adjusted in substantially axial alignment with the work piece 24, 20 with its face 32 in close position determining engagement with face 25 of the work piece. Consequently, if the work piece be pressed against the head 31, this head will automatically position the work piece in proper 25 relation to the operative surfaces of the grinding and regulating wheels. Its anti-friction mounting will permit of its free rotation with the work piece, while the sliding contact of faces 25 and 32 will permit of any slight 30 transverse play necessitated by out of round condition of the work piece or variation in its position in the throat due to reduction of diameter during the grinding. A suitable bell flange or projecting cap 33 is preferably 35 utilized to protect the bearings or mountings of spindle 30.

To support the work in engagement with head 31 during the grinding and to facilitate introduction of the work into the grinding 40 throat and removal therefrom, use is made of the mechanism illustrated in the right-hand portion of Figure 3. This mechanism includes a supplemental bracket or support 34, rising from bracket 14 and bearing the adjustable head 35, in which is slidably a rotatable supported plunger bar 36 having the longitudinally extending groove 37 inwardly terminating in a diagonally disposed or cam groove 38. A pin 39, disposed in head 35, 45 projects into the slot 37-38 and by its engagement limits and determines the movement of bar 36 with respect to the head. The bar carries on its inner end a collar 40, provided with an arm 41 terminating in lug 42. 50 Adjustably mounted on the face of lug 42 are work engaging fingers 43 and 44, retainable in properly adjusted position by bolts 45. It will be noted that a work receiving space is provided between arm 41 and the fingers 43 55 and 44, the fingers engaging the smaller diameter 46 of the work piece. When the head is in retracted position, the work piece will consequently be supported in slightly tilted relation on the fingers, due to the greater 60 weight of the enlarged outer end thereof, the

fingers themselves being adjusted to lie in a plane slightly below that occupied by the work during the grinding.

Bar 36 is counterbored, as at 47, to receive plunger 48 outwardly urged by spring 49 bearing against flange 50 of the plunger at one end and against the base of the recess at the other. An inserted guide bushing 51 limits the outward movement of the plunger, permitting the same to project a limited distance beyond the end of the bar when flange 50 is seated against the end of the bushing. The normal projection of the plunger, however, is insufficient to contact with the work when it is initially placed within the retaining fixture.

In the form of the invention particularly illustrated in Figures 1 to 3, inclusive, of the drawings, bar 36 is shown as formed with a reduced outer end, as at 52, on which is rotatably mounted collar 53 of handle 54, being retained in position by terminal nut 55. This handle has a spring pressed locator detent 56, engageable in a socket 57 of bar 36, tending to retain same in locking position from automatically disengaging the bar to permit rotation of the handle thereto when manually actuated. The collar portion 53 of the handle is provided with a locking pin or lug 58, adapted to ride along incline 59 of lock plate 60, adjustably supported on head 35 by pins 61, having the interposed springs 62 and terminally provided with adjusting nuts 63. When the handle is oscillated in a clockwise direction, lug 58 will be shifted from the full line position indicated in Figure 6 onto the plane interface of the lock plate, as indicated by the dotted circle in said figure. When the handle is so shifted, detent 56 will tend to retain same against accidental dislodgment and rod 36 will be positively retained in its inward position, as shown in Figure 3 of the drawings.

When handle 54 is rocked in a counter-clockwise direction, the effect is a disengagement of the locking lug 58. The handle may then be drawn forwardly, shifting with it rod 36, which will cause fingers 43 and 44 to engage the flange portion 64 of the work piece and retract same, pin 39 limiting the movement of rod 36 to a purely axial sliding. Continued retraction of the handle and rod, however, brings pin 39 into portion 38 of the slot, automatically imparting a counter-clockwise rotation to the rod of sufficient amount that the lefthand finger 44 no longer laterally supports the work and the same may be either manually withdrawn or allowed to roll out into a suitable trough or receptacle, as indicated at 65. On the inception of return movement of handle 54, bar 36 is again automatically oscillated to move the open pocket formed on its end by the fingers, into a work supporting position, continued movement bringing the work inward until the

head 31 contacts with the lower portion of the slightly tilted work piece supported therein. Subsequent movement causes the projecting end of plunger 48 to contact with the front face of the work, resiliently urging the same rearwardly, when the work will be tilted to bring its face 25 in proper engagement with face 32 of head 31, and its periphery suitably supported on work rest blade 21 and 10 out of engagement with fingers 43 and 44. The part is then properly supported for performance of the standard centerless grinding operation thereon and formation of a cylindrical surface normal to the previously 15 formed face 25.

It will be understood that the grinding here contemplated is what is generally known as in-feed grinding, in which the stock removal is effected by positioning of the work 20 piece within the grinding throat, a subsequent narrowing of the throat causing an approach of the operative surfaces of the grinding and regulating wheels engaging the work to a prescribed position, causing the desired 25 stock removal, and an ensuing opening of the throat to release the work and permit its ready withdrawal. In Figure 1, the mechanism illustrated for accomplishing this result includes an adjusting screw 66 swiveled 30 in bracket 67 on the bed 10 and in threaded engagement with a rotary nut 68 swiveled to the regulating wheel unit 16. This nut is provided with an actuating handle 69, oscillatable within prescribed limits, the rotation 35 of the nut on the screw causing a back and forth movement of slide 13 with the work rest and regulating wheel unit thereon. In addition, the position of the parts may be varied to compensate for wheel wear, original 40 set-up of the machine or the like by rotative adjustment of the screw 66 as by pilot wheel 70.

In Figures 7, 8 and 9 there has been illustrated what may be termed a substantially 45 complete automatic mechanism in which the machine parts are substantially as just described but in which the back and forth movement for variance of the grinding throat is effected by a block 71, slidably supported in 50 the sub-frame 72 and having the nut engaged therein. Linkage 73 connects this block with rock arm 74, having a roller portion engaged in face groove 75 of cam 76, to which power is suitably applied as from motor 77. This 55 cam has the barrel portion 78 provided with a cam groove 79, engaging roller 80 on plunger 81. This plunger is pivotally associated with an arm 82 on rock shaft 83, which extends longitudinally of the bed in suitable 60 bearings 84 and has an actuating rock arm 85, coupled with shifter spool 86 on bar 36. In the operation of this form of the invention, as the cam 76-78 is rotated, it 65 serves to effect cyclic opening and closing of the grinding throat for introduction, grind-

ing and removal of the work piece. At the same time, the cam track 79, through the connections mentioned, oscillates arm 85 in a manner to retract plunger 36 during the widening of the grinding throat to a point 70 where the rod twists and the work is automatically ejected. The cam then imparts a partial inward movement to plunger 36, restoring the lug 42 to work retaining position and maintaining it immovable in this position a sufficient period of time to enable the operator to insert a new work piece, the regulating wheel being held substantially stationary as respects reciprocating movement. Continued rotation of the cam then moves 80 member 36 inward, positioning the work piece on the work rest and in contact with the regulating wheel, locking the bar in this position with plunger 48 exerting the desired pressure to clamp the work against rotary 85 positioning head 31. The parts are maintained in this position while the cam rotates, to produce the desired in-feed of the regulating wheel, forcing the work against the grinding wheel for proper stock removal and 90 until the regulating wheel movement has been reversed and the work released from the combined grip of grinding and regulating wheels, when the bar is retracted for ejection 95 of the work piece. This, it will be understood, is a continuous cyclic operation in which the only duty of the operator is the supplying of the work pieces, a function also accomplishable, if preferred, by the use of suitable hopper mechanism forming no part 100 of the present invention and not therefore illustrated or described.

From the foregoing description, considered in conjunction with the drawings, the advantages of the machine should be readily apparent and it will be noted that there has been provided an improved mechanism for introducing a work piece into the grinding throat of a centerless grinder in a manner to permit of grinding of a terminal portion of 105 the work or, when the work is in an unbalanced condition, with its center of gravity on the outside of the grinding throat. It will further be noted that the mechanism is of such nature that the unbalanced work piece is suitably, preferably, resiliently urged and maintained in a definite position as respects the plane of the grinding wheel, in such manner that the ground surface will be produced normal or in desired relation 110 to a different portion of the work piece.

It will further be noted that improved means have been provided, by which a difficult to handle work piece, of short length bringing the same close to the high speed 115 grinding wheel, may be satisfactorily handled with entire safety to the operator, may be readily withdrawn from operative position within the machine and automatically 120 ejected.

Attention is further invited to the fact that the entire series of operations may be performed as an automatic cycle, requiring minimum of attention or skill on the part of the operator, and that the cost of production is therefore greatly reduced and necessary idle or non-grinding time of the machine minimized.

I claim:

1. The combination with a centerless grinder, including opposed grinding and regulating wheels and an intermediate work support, of an oscillatable axially movable work positioning member disposed adjacent to the throat, and means for imparting successive axial and oscillatable movements to the holder to present, withdraw and eject a work piece.

2. The combination with a centerless grinder, including opposed grinding and regulating wheels and an intermediate work support providing a work receiving throat, of a rotary work locating member disposed adjacent the throat, and means for maintaining a work piece in terminal engagement with the member while within the throat and supported by the work rest.

3. The combination with a centerless grinder, including opposed grinding and regulating wheels and an intermediate work support providing a work receiving throat, of a rotary work locating member disposed adjacent the throat, and means for maintaining a work piece in terminal engagement with the member while within the throat and supported by the work rest, said means including a yieldable actuated pressure device.

4. The combination with a centerless grinder, including opposed grinding and regulating wheels and an intermediate work support providing a work receiving throat, of a rotary work locating member disposed adjacent the throat, means for maintaining a work piece in terminal engagement with the member while within the throat and supported by the work rest, said means including a yieldable actuated pressure device, and means for axially withdrawing and laterally ejecting a finished work piece.

5. The combination with a centerless grinder, including opposed grinding and regulating wheels and an intermediate work rest providing a grinding throat, of a rotary work positioning member aligned with the throat for engaging and positioning a work piece on the work rest within the throat during the grinding operation, means for urging the work piece into engagement with said member, and means for securing the parts in adjusted position.

6. The combination with a centerless grinder, including opposed grinding and regulating wheels and an intermediate work rest, of a work positioning member aligned with the space between grinding and regu-

lating wheels for engagement with a work piece to establish the axis thereof, and a reciprocable work carrier having a work supporting portion and a supplemental relatively movable portion for engagement with the work piece to maintain the work piece in engagement with the positioning member during the grinding operation.

7. The combination with a centerless grinder, including opposed grinding and regulating wheels and an intermediate work rest, of a work positioning member aligned with the space between grinding and regulating wheels for engagement with a work piece to establish the axis thereof, and a reciprocable work carrier having a work supporting portion and a supplemental relatively movable portion for engagement with the work piece to engage the work piece and move same out of engagement with the primary support therefor.

8. The combination with a centerless grinder, including opposed grinding and regulating wheels and an intermediate work rest, of a work positioning member aligned with the space between grinding and regulating wheels for engagement with a work piece to establish the axis thereof, a reciprocable work carrier having a work supporting portion and a supplemental relatively movable portion for engagement with the work piece to engage the work piece and move same out of engagement with the primary support therefor, and means for resiliently urging the supplemental member into operative engagement with the work piece.

9. In combination with a centerless grinder, including opposed grinding and regulating wheels and an intermediate work rest, of a work positioning member disposed in alignment with the throat between grinding and regulating wheels, a reciprocable work holder movable toward and from the grinding throat to shift a work piece into the throat in engagement with the positioning member, releasable means for securing the parts in engaged position, and means for additionally shifting the carrier to eject a work piece on retracting movement thereof.

10. A work positioning mechanism of the character described, including a carrier for loosely engaging a work piece, a yieldable clamp member on the carrier for engagement with the work piece, and means introposable in the path of movement of the work piece for urging the same against the clamp member.

11. The combination with a centerless grinder, including opposed grinding and regulating wheels and an intermediate work rest, of a work limiting member projectable in the path of movement of a work piece in the grinding throat, and a work carrier movable toward and from the grinding throat in position to the grinding member having a

normal work supporting portion and an adjacent clamp plunger, means for limiting the plunger in a clamping direction, and means for shifting the device as an entirety in the direction of the grinding throat whereby the engagement of the limiting member with the work will render the plunger operative to retain the work in proper aligned grinding position.

10 12. The combination with a centerless grinder, including opposed grinding and regulating wheels and an intermediate work rest, of a work limiting member projectable in the path of movement of a work piece 75
15 in the grinding throat, and a work carrier movable toward and from the grinding throat in position to the grinding member having a normal work supporting portion and an adjacent clamp plunger, means for 80
20 limiting the plunger in a clamping direction, means for shifting the device as an entirety in the direction of the grinding throat whereby the engagement of the limiting member with the work will render the plunger operative to retain the work in proper aligned 85
25 grinding position, means for automatically imparting movement to the carrier, and additional means for automatically varying the width of the grinding throat in synchronism 90
30 with the carrier.

13. In a device of the class described the combination of a bed, a pair of opposed grinding and regulating wheels carried thereby and forming a grinding throat therebetween, a work rest blade subtending the grinding throat, and a work positioning and ejecting mechanism for placing in and removing work pieces from the grinding throat comprising a bar axially shiftable relative to the grinding throat, and means carried by the bar for supporting a work piece from a loading position to a position within the grinding throat and placing said work piece on the work rest blade.

45 14. In a device of the class described the combination of a bed, a pair of opposed grinding and regulating wheels carried thereby and forming a grinding throat therebetween, a block beneath the grinding throat, a work rest blade supported by the block, a bearing rising from the block, a work positioning member slidably actuated through the bearing, means on the member for supporting and carrying a work piece from a loading position to the throat and reverse, and means on the member for actuating same.

50 15. In a device of the class described the combination of a bed, a pair of opposed grinding and regulating wheels carried thereby and forming a grinding throat therebetween, a block beneath the grinding throat, a work rest blade supported by the block, a bearing rising from the block, a work positioning member slidably actuated through the bearing, means on the member for supporting and

carrying a work piece from a loading position to the throat and reverse, means on the member for actuating same, a second bearing carried by the block in opposition to the sliding bearing, and means rotatably supported by the second bearing for engagement with the work when in the grinding throat to position the work relative thereto.

55 16. In a device of the class described the combination of a bed, a pair of opposed grinding and regulating wheels carried thereby and forming a grinding throat therebetween, a block beneath the grinding throat, a work rest blade supported by the block, a bearing rising from the block, a work positioning member slidably actuated through the bearing, means on the member for supporting and carrying a work piece from a loading position to the throat and reverse, means on the member for actuating same, a second bearing carried by the block in opposition to the sliding bearing, and means rotatably supported by the second bearing for engagement with the work when in the grinding throat to position the work relative thereto, 90
80 and means for independently adjusting the bearings relative to the block to position said bearings relative to the work.

95 17. The combination with a centerless grinder including opposed grinding and regulating wheels and an intermediate work rest forming a three point grinding throat, of means for inserting a work piece within the grinding throat on the work rest blade comprising a bearing, a slidable member carried by the bearing and slidable relative thereto, a cam slot within the member for determining the direction of movement thereof, and means carried by the bearing cooperating with the cam slot whereby the slid- 100
105 able member will successively position a work piece carried thereby within the grinding throat, retract said work piece from the throat and laterally discharge the work.

110 18. In a device of the class described the combination of a bed, a pair of opposed grinding and regulating wheels carried thereby and forming a grinding throat therebetween, one of said wheels being translatable relative to the bed for varying the width of the grinding throat, a work rest blade within the throat, and means carried by the bed in alignment with the throat axially shiftable relative thereto for placing work pieces within the throat and removing same therefrom 115
120 when the said throat is enlarged.

125 19. In a device of the class described the combination of a bed, a pair of opposed grinding and regulating wheels carried thereby and forming a grinding throat therebetween, one of said wheels being translatable relative to the bed for varying the width of the grinding throat, a work rest blade within the throat, means carried by the bed in alignment with the throat axially shiftable rela- 130

tive thereto for placing work pieces within the throat and removing same therefrom when the said throat is enlarged, and manual means for actuating one of the wheels and the work positioning and ejecting member in timed sequence.

20. In a device of the class described the combination of a bed, a pair of opposed grinding and regulating wheels carried thereby and forming a grinding throat therebetween, one of said wheels being movable relative to the bed toward and from the other to vary the width of the grinding throat, means in alignment with the grinding throat for supporting a work piece for movement axially of the grinding throat, and automatic means for actuating one of the wheels relative to the other and the work positioning and ejecting means in timed sequence whereby the grinding throat is open, a work piece placed therein, the grinding throat contracted to reduce the work to the desired size, subsequently reopening the grinding throat and ejecting the work therefrom.

25. In testimony whereof I affix my signature.
FREDERICK J. THELER.
